UNITED STATES PATENT OFFICE

ERVIE A. FERRIS, OF WESTWOOD, CALIFORNIA

OFFSET FOR LOG CARRIERS

Application filed March 31, 1928. Serial No. 266,250.

My invention relates to improvements in an offset for log carrier, and it consists in the combinations, constructions, and arrangements hereinafter described and claimed.

5 An object of my invention is to provide an offset for a log carrier which automatically moves a log laterally at the end of the cutting operation, so that the log can be returned for the next cut without it interfering with the band saw. The carrier supporting the log is shifted laterally for this purpose, and I provide novel means for accomplishing this as soon as the carrier starts on its return movement. Additional means 10 is provided for causing the carrier to stop and start on its return movement without moving laterally, thus permitting the log to be stopped when partially cut, and to be reversed in its movement without having the saw interfered with by a lateral movement.

15 A further object of my invention is to provide a device of the type described that has means for taking up the shock caused by a log rolling upon the carrier into position. This means also performs the additional function of moving the carrier back into a 20 position for the next cut when the carrier has been returned to its starting point.

25 Other objects and advantages will appear in the following specification, and the novel features of my invention will be particularly pointed out in what I hereinafter claim.

30 My invention is illustrated in the accompanying drawings forming a part of this application, in which:

35 Figure 1 is a top plan view of the device;

Figure 2 is a side elevation;

40 Figure 3 is an end elevation showing a log holding device positioned on the carrier;

Figure 4 is an enlarged detail of a portion of the device; and

45 Figure 5 is a view similar to Figure 4, but showing the parts in a different position.

In carrying out my invention I provide a carrier 1 that is slidably mounted upon shafts 2 so that the carrier can move laterally on the shafts. The shafts carry V-shaped wheels 3 and flat flanged wheels 4. The wheels 3 ride upon a rail 5 and this rail

guides the carrier. The wheels 4 ride upon a flat rail 6. This is standard construction.

Figure 1 shows how each shaft 2 is threaded at 7 and 8 for receiving lock nuts 9 and 10. These nuts bear against thrust washers 11 and 12, which in turn bear against the end of a bearing 13. An adjustment of the nuts 9 and 10 will correctly position the carrier 1 upon the shafts 2.

The bearings 13 are connected to each other in pairs by castings 14. These castings carry two cylinders 15 and the carrier carries two cylinders 16 and I will hereinafter refer to the cylinder 15 as the cushioning cylinder, and the cylinder 16 as an offset cylinder.

In the cylinder 15 I mount a cushioning piston 17, see Figure 1, and this piston is connected by a rod 18 to the carrier 1. It will be seen from this construction that a movement of the piston 17 will move the carrier 1 laterally upon the shafts 2. The cylinders 15 are connected by air pipes 19 to a common main line pipe 20. The pipe 20 carries air under a constant pressure and normally the pistons 17 will keep the carrier in a position where a band saw 21, see Figure 3, will cut through a log 22.

At this point it might be well to note that the pistons 17 act as a cushioning means for carrier 1 when a log is rolled upon the carrier. Reference to Figure 3 shows that the log 22 will strike knees 23 of a log holding member. These knees are secured to the carrier and therefore when the log strikes them it will tend to move the carrier laterally upon the shafts 2. This movement causes the pistons 17 to move in the cylinders 15 and partially compress the air within the cylinders. In this way the pistons act as shock absorbing means. When the shock has been absorbed the pressure within the pipes 19 is sufficient to move the carrier 1 back into cutting position. The log 22 is held by upper and lower tong dogs 24 and 25.

The carrier will remain in the position shown with respect to the shafts 2 during the entire cutting operation. The carrier is moved laterally upon the shafts during its return movement, and is held in this position during the entire movement. The means for

accomplishing this is shown in Figures 1, 4, and 5. Upon one of the wheels 3 I mount a lever 26. This lever has a curved portion 27 partially enclosing the hub 28 of the 5 wheel. An arcuate strap 29 is hinged at 30 to the lever 26, and is held in frictional contact with the hub 28 by means of a bolt 31 and a spring 32. Reference to Figure 4 shows that a rotation of the wheel 3 in a 10 clockwise direction will swing the lever 26 to the right and an opposite rotation will swing the lever to the left. The extent of this movement is controlled by a stop plate 33, see Figure 1. This plate is carried by 15 the carrier 1 and has projections 34 and 35 that extend into the path of the swing of the lever 26. Figure 4 shows how the stop 34 prevents further movement of the lever 26 while the wheel 3 continues to rotate in a 20 counter-clockwise direction. Figure 5 shows the lever swung into the opposite position by a clockwise rotation of the wheel 3. The lever in this instance is held by the stop 35.

A valve 36 has its arm 37 connected to 25 the lever 26 by a link 38. This valve places pipes 39 and 40 in communication with a pipe 41 when the lever is in the position shown in Figure 4. The pipe 41 taps from the pipes 19 and is controlled by a manually 30 operated valve 42.

When air is admitted to the pipes 39 and 40 it passes to the offset cylinders 16. In the cylinders are mounted offset pistons 43. These pistons bear against the castings 14 35 and have sufficient force to move the carrier 1 upon the shafts 2.

From the foregoing description of the various parts of the device, the operation thereof may readily be understood.

40 Assume that the carrier has completed its cutting stroke, i. e., the band saw has entirely cut through the entire length of the log 22. It is now necessary for the carrier to return the log for the next cut and during 45 this return movement the log must be moved laterally a slight distance away from the band saw. During the time the carrier has been moving the log into engagement with the saw, the lever 26 has been held against 50 the stop 35. As soon as the carrier starts on its backward movement, the lever will be swung into the opposite position and air will instantly be admitted to the cylinders 16 and 55 will force the pistons 43 against the castings 14. The castings being fixed with respect to the shafts 2 will cause the carrier 1 to move laterally a sufficient distance for the log to clear the saw. This lateral movement will drive the pistons 17 down into the cylinders 15 a slight distance. The areas of the pistons 43 are much larger than those of the pistons 17 and therefore the increased air pressure against these pistons is sufficient to overcome the resistance offered by the pistons 60 17. The valve 36 is kept open during the

entire travel of the carrier back to the starting position. When the carrier starts on its next cutting operation, the lever 26 is again swung and cuts off the air to the pistons 43. The constant air pressure in the pipes 19 will 70 now force the pistons 17 back to their normal position and the carrier will be moved laterally and will carry with it the log, correctly positioning the log for the next cut.

In case a partial cutting has been made 75 in the log and it is desired to return the log to the starting position prior to a completion of the cut, the operator closes the valve 42, see Figure 1, and cuts off the air supply to the valve 36. A movement of the lever 26 80 and valve 36 will therefore have no effect upon the pistons 43. This will prevent the carrier from being moved laterally.

Although I have shown and described one embodiment of my invention, it is to be understood that the same is susceptible of various changes and I reserve the right to employ such changes as may come within the scope of the invention as claimed.

I claim:

1. A device of the type described comprising a plurality of shafts, wheels supporting said shafts, a carrier mounted on said shafts and having a lateral movement with respect thereto, cylinders carried by said shafts, pistons mounted in said cylinders, and being connected to said carrier, means for maintaining a constant pressure of air upon said pistons, auxiliary cylinders, auxiliary pistons mounted in said cylinders of a larger size than said first named pistons, means controlled by the longitudinal movement of the carrier for directing air into said auxiliary cylinders during a part of the movement of said carrier, whereby said auxiliary pistons will 100 move said carrier laterally upon said shafts.

2. A sawmill carriage comprising a plurality of shafts, a carrier supported by said shafts and having a lateral movement with respect thereto, a common source of air pressure, means controlled by the air pressure for yieldingly holding the carrier against lateral movement, a second means actuated by the air pressure and controlled by the longitudinal movement of the carrier for exerting a 115 greater pressure against the carrier than that exerted by the first means, said second means moving the carrier laterally.

3. A device of the type described comprising a plurality of shafts, wheels supporting said shafts, a carrier mounted on said shafts and having a lateral movement with respect thereto, cylinders carried by said shafts, pistons mounted in said cylinders, and being connected to said carrier, means for maintaining a constant pressure of air upon said pistons, auxiliary cylinders, auxiliary pistons mounted in said cylinders of a larger size than said first named pistons, and means for applying air against said auxiliary pistons 120 125 130

and under the same pressure as applied against the first mentioned pistons, whereby said auxiliary pistons will move said carriage laterally upon said shafts.

5 4. A sawmill carriage comprising a plurality of shafts, a carrier supported by said shafts and having a lateral movement with respect thereto, a common source of air pressure, means controlled by the air pressure for yieldingly holding the carrier against lateral movement, a second means actuated by the air pressure and automatically controlled for exerting a greater pressure against the carrier than that exerted by the 10 first means, said second means moving the carrier laterally.

15 5. A device of the type described comprising a plurality of shafts, wheels supporting said shafts, a carrier mounted on said shafts and having a lateral movement with respect thereto, cylinders carried by said shafts, pistons mounted in said cylinders, and being connected to said carrier, means for maintaining a constant pressure of air upon said 20 pistons, auxiliary cylinders, auxiliary pistons mounted in said cylinders of a larger size than said first named pistons, and means for applying air against said auxiliary pistons and under the same pressure as applied 25 against the first mentioned pistons, whereby said auxiliary pistons will move said carriage laterally upon said shafts, said first- 30 named pistons at all times pressing against air under pressure, whereby said carrier can 35 have a slight lateral movement for absorbing the shock of receiving a log.
